UNITED STATES PATENT OFFICE.

FREDERIC G. NICOLAUS, OF CLEVELAND, OHIO, ASSIGNOR TO AMERICAN STOVE COMPANY, OF ST. LOUIS, MISSOURI, A CORPORATION OF NEW JERSEY.

LIGHTER FOR GAS-STOVES.

1,143,060.

Specification of Letters Patent. Patented June 15, 1915.

Application filed December 21, 1914. Serial No. 878,367.

To all whom it may concern:

Be it known that I, FREDERIC G. NICOLAUS, a citizen of the United States, residing at Cleveland, in the county of Cuyahoga and State of Ohio, have invented certain new and Useful Improvements in Lighters for Gas-Stoves, of which the following is a specification, reference being had therein to the accompanying drawing.

10 My invention relates to improvements in lighters for gas stoves.

The object of my invention is to provide a lighter located between the four burners of a stove and so arranged and constructed 15 that the flame will travel across to the several burners and ignite the same, and also providing a pilot light arranged centrally within the lighter and fed with gas by a separate pipe leading through the supply 20 pipe of the burner whereby the lighter will instantaneously ignite therefrom.

Another object of my invention is to provide a lighter of this character which will produce two flashes to ignite the burners by 25 a single operation of the valve and thus insure of the ignition of the burners during one or the other of the flashes.

A further object of my invention is to provide a simple, cheap and effective lighter 30 of this character adapted to be readily applied to the ordinary gas stove and having certain details of structure and operation hereinafter more fully set forth.

In the accompanying drawing, Figure 1 is 35 a perspective view of my improved lighter. Fig. 2 is a side elevation showing the burner and pilot light in section. Fig. 3 is a top plan view of Fig. 1 showing the controlling valve in section, and also showing the bell 40 surrounding the burner. Fig. 4 is a dia-grammatical view of a stove showing my lighter applied thereto.

Referring now to the drawings, 1 represents the casing of my improved valve which 45 is provided with a tapering central opening 2 therethrough in which is arranged a correspondingly shaped turning plug 3 having a transverse passage 4 therethrough. The casing 1, is provided with an opening 5 com-50 municating with its rear end and having its forward end communicating with the central opening 2. Communicating with the opening 2 at the forward end of the casing is a passage 6 which has its outer end in

communication with the enlarged internal 55 threaded recess 7. The plug 3 above the casing is provided with a housing 8 having a spring therein adapted to hold the valve in its normal position shown in Fig. 3 of the drawing. The said housing 8 is provided 60 with a handle 9 by means of which the plug is oscillated. The lower end of the plug extends below the housing and is screw-threaded and has screwed thereon a nut 10. Between the nut 10 and the housing 1 and sur-65 rounding the extension of the turning plug is a coil spring 11 which normally holds the turning plug in a downward position to form a tight joint with the housing to prevent the leakage of gas therefrom. 70

Screwed within the internally screw-threaded recess 7 of the housing is a pipe 12 which leads outwardly and has screwed thereon a casting 13 which will be later more fully described. The housing 1 is pro-75 vided with a bypass 14 extending around the turning plug 3 and communicating with the pipe 15 arranged within the pipe 12 as clearly shown in Figs. 2 and 3.

The casting 13 is screw-threaded on the 80 pipe 12 and has a passage 16 leading diagonally upward to the enlarged recess 17 ar- ranged in the upper end of the casting.

Removably secured in the recess 17 is the burner or lighter proper 18 which is pro-85 vided at its upper end with the horizontally arranged openings 19 through which the gas passes and flashes outwardly as will be hereinafter more fully described.

The portion 19' of the casting 13 is adapt-90 ed to support the bell 20 having the usual opening through which the flame flashes through the openings 19 as fully described in a co-pending application executed on even date, Serial No. 658, filed January 5, 95 1915.

The pipe 15 extends inwardly within the casing as indicated at 21 and communicates with a vertically disposed passage 22 com-100 municating with the pipe 23 which extends upwardly through the burner 18 and has its upper end 24 open and which forms the pilot light which is continuously burning. In order to control the amount of gas passing to the pilot burner, I provide the casting with 105 a nipple 25 into which is screwed a screw valve 26 having the tapered inner end 27 extending within the end 21 of the pipe 15

and whereby the gas is controlled to the passage 22 for increasing or decreasing the pilot light.

In Fig. 4, the bell 20, as shown, is located centrally between the burners 28, 29, 30 and 31 and there are arranged four openings 19 in the burner 18 to shoot the flame out through the bell in the direction of the arrow shown in Fig. 4 to ignite the several burners.

From the foregoing description it will be seen that when the turning plug is turned with the passage 4 in the direction shown in dotted lines Fig. 3, a certain amount of gas has passed through the passage 4 to the pipe 12 and out through the passage 16 to the burner 18 and flashed outwardly through the openings 19 and ignited by the flame at the pilot burner. This pilot burner, as heretofore described, is continuously receiving gas through the bypass 14 and the pipe 15 and is therefore continuously burning. When the turning plug is released, the spring within the drum 8 forces the plug 3 back to the position shown in Fig. 3 shown in full lines, and a second supply of gas passes through the passage 4 as it registers with the passage 5 and thus supplies a second supply of gas to the pipe 12 to cause a flash from the openings 19 clearly shown in Fig. 2 of the drawing.

Having thus fully described my invention what I claim and desire to secure by Letters Patent is:

35 1. A lighter of the character described comprising a vertically disposed burner having horizontally arranged openings at its upper end, a gas supply for the burner, and a pilot light within the upper end of the burner and having a gas supply extending down through the burner.

40 2. A lighter of the character described comprising a vertically disposed burner having horizontally arranged openings at its upper end, a supply for the said burner, a pilot light within the upper end of the burner, a gas supply for the pilot light extending downwardly through the burner and through the gas supply for the main burner.

45 3. A lighter of the character described comprising a vertically disposed burner having gas openings adjacent its upper end, a gas supply pipe for the said burner, a pilot light within the upper end of the burner, a gas supply for the said pilot light and extending downwardly through the burner and through the main gas supply pipe, a valve controlling the supply of gas to the main burner, and a needle valve for regulating the gas pressure in the pilot light supply.

50 4. A lighter of the character described comprising a vertically disposed burner having horizontally arranged gas discharge openings adjacent its upper end, a gas supply pipe for the burner, a pilot burner with-

in the upper end of the main burner, a gas supply for the said pilot burner extending downwardly through the main burner and through the gas supply pipe of the main burner, a valve within the supply pipe of the main burner, and said valve constructed and arranged to supply the pilot light supply with a constant flow of gas.

5 5. A lighter of the character described comprising a casting having an opening in its upper end, a vertically disposed burner within the said opening and having horizontally arranged discharge openings adjacent its upper end, a gas supply connected to the casting and having a passage communicating with the lower end of the gas burner, a pilot burner within the upper end of the main burner, a supply pipe for the said pilot burner and extending downwardly through the main burner and communicating with a passage in the casting, a supply pipe communicating with said passage and extending outwardly through the main gas supply pipe, a valve within the main supply pipe and adapted to control the gas to the main burner, and said valve constructed and arranged to supply the pilot light supply with a constant flow of gas.

10 6. A lighter of the character described comprising a vertically disposed burner having horizontally arranged openings adjacent its upper end, a pilot burner within the upper end of the main burner, a supply pipe for the main burner, a supply pipe for the pilot burner and extending through the supply pipe for the main burner, a valve carried by the supply of the main burner and controlling the gas thereto, and said valve constructed and arranged for maintaining a constant gas pressure to the pilot burner.

15 7. A lighter of the character described comprising a vertically disposed burner having horizontally arranged openings adjacent its upper end, a pilot burner within the upper end of the main burner, a gas supply pipe for the main burner, a gas supply pipe for the pilot burner and extending through the main supply pipe, a valve controlling the supply of gas to the main burner supply pipe and having a by-pass adapted to maintain a constant gas pressure to the pilot burner.

20 8. A lighter of the character described comprising a main burner, a pilot burner within the main burner, a gas supply pipe for the main burner, a gas supply pipe for the pilot burner and extending through the main gas supply pipe, and a valve controlling the gas supply to the main supply pipe and allowing a constant pressure to the pilot light.

25 9. A lighter of the character described comprising a main burner, a pilot burner within the main burner, a supply pipe for the main burner, a supply pipe for the pilot burner,

burner, and extending through the main supply pipe, a spring closed turning plug for the main supply pipe and adapted to supply a constant gas supply to the pilot light where-
5 by the main burner receives two charges of gas during each operation of the valve.

10. A lighter of the character described comprising a casting having a recess in its upper end, a burner within the said recess and having horizontally arranged openings adjacent its upper end, said casting having a pipe connected thereto and having an obliquely arranged passage communicating with the burner, a pilot burner within the 15 upper end of the main burner, a pipe leading from the pilot burner through the main burner, and communication with a passage in the casting, a supply pipe for said passage and extending through the main gas 20 supply pipe, a valve regulating the gas pressure through the said passage for controlling the gas pressure of the pilot burner.

11. The combination with a series of burners, of a lighter located between the 25 burners comprising a burner having horizontally arranged openings arranged in a radial line with the burners, a gas supply for the said burner, a pilot burner within the main burner and having a separate gas 30 supply within the gas supply of the main burner, and a valve carried by the main supply pipe for controlling the supply of gas to the main burner and allowing a constant gas pressure to the pilot burner.

35. 12. The combination with a series of burners, of a lighter comprising a vertically disposed burner having horizontally arranged openings adjacent its upper end and in a radial line with the burners, a pilot 40 burner within the upper end of the main burner, a gas supply for the main burner, a gas supply for the pilot burner and extending through the gas supply of the main burner, a needle valve for regulating the gas 45 pressure in the supply for the pilot burner, a turning plug within the main supply pipe, and normally spring closed whereby two charges of gas are allowed to pass to the main burner during each operation of the 50 plug, said plug having means for allowing a constant flow of gas to the pilot supply pipe.

13. A lighter of the character described

comprising a casting having an opening in its upper end, a vertically disposed burner 55 within the said opening and having horizontally arranged discharge openings adjacent its upper end, a gas supply connected to the casting and having a passage communicating with the lower end of the gas 60 burner, a pilot burner within the upper end of the main burner, a supply pipe for the said pilot burner and extending downwardly through the main burner and communicating with the passage in the casting, and a 65 supply pipe communicating with said passage and extending outwardly through the main supply pipe.

14. A lighter of the character described comprising a casting having an opening in 70 its upper end, a vertically disposed burner within the said opening and having horizontally arranged discharge openings adjacent its upper end, a gas supply connected to the casting and having a passage communicat- 75 ing with the lower end of the gas burner, a pilot burner supply extending upwardly through the burner and having its upper end at a point flush with the upper end of the burner, and having its opposite end ex- 80 tending downward through the main burner and communicating with the passage in the casting, and a supply pipe communicating with said passage and extending outwardly through the main gas supply pipe. 85

15. A lighter of the character described comprising a casting having an opening in its upper end, a vertically disposed burner within said openings and having horizontally arranged discharge openings adjacent 90 its upper end, a gas supply connected to the casting and having a passage communicat- 95 ing with the lower end of the gas burner, and a pilot light supply pipe extending through the casting and through the main 100 burner and ending at a point flush with the upper end thereof and forming a pilot burner at the center of the main burner, the opposite end of the pilot supply pipe extending through the main supply pipe.

In testimony whereof I hereunto affix my signature in the presence of two witnesses.

FRED. G. NICOLAUS.
